UNITED STATES PATENT OFFICE

132,998

DESIGN FOR AN ADVERTISING DEVICE OR SIMILAR ARTICLE

Pierre L. Poffet, New York, N. Y.

Application February 5, 1942, Serial No. 105,647

Term of patent 14 years

To all whom it may concern:

Be it known that I, Pierre L. Poffet, a citizen of Switzerland, residing in the city, county, and State of New York, have invented a new, original, and ornamental Design for an Advertising Device or Similar Article, of which the following is a specification, reference being had to the accompanying drawing forming a part thereof.

vertising device or similar article, showing my new design.

Figure 2 is a side elevation.

The back of the device is plain.

I claim:

The ornamental design for an advertising device or similar article, as shown and described.

PIERRE L. POFFET.
